SAFETY BALL TRAP

Francis C. Sams, Bath, N. Y.

Application February 17, 1944, Serial No. 522,817

4 Claims. (Cl. 273—47)

My invention relates to bowling alleys, and more particularly to an improved safety ball trap for a ball in motion on the ball return runway thereof.

Insofar as I am aware, it is usual for bowling establishments to purchase, install and operate bowling alleys completely devoid of any means for preventing a returning ball from rolling back toward the ball pit should the ball have insufficient momentum in its travel along the return runway to carry it up the incline and on to the ball rack at the runway end. Such lack of momentum is presumably due to a number of causes, and such failure of the ball to roll up and on to the ball rack often occurs notwithstanding the fact that the ball return runway may be perfectly designed. Atmospheric conditions may be one cause of such failure; lack of cleanliness another; or the pin boy may be at fault. As to atmospheric conditions, obviously if the runway is damp and sticky, the ball will not roll as freely and smoothly therealong as would be the case if the runway were dry. The same is true if the runway is dusty and dirty. In the case of the pin boy, the fault may lie in an improper handling of the ball. A slight backspin imparted to the ball by the pin boy at the moment of its release not infrequently prevents the ball from attaining the required momentum. Regardless of the cause, backward rolling movement of a bowling ball, once on the return runway, is to be avoided if possible. Otherwise, a number of objectionable things can happen. If the player awaiting the return of the ball attempts to retrieve it during its backward rolling movement, there is always the possibility that he may get his fingers badly injured. This for the reason that by the time he reaches the backwardly rolling ball, the next ball to be returned along the runway may be approaching and may come in contact with his fingers at the very moment he attempts to retrieve the first returned ball. If, on the other hand, no attempt is made to retrieve the backwardly rolling ball, it is more than likely it and the next approaching ball will collide with considerable impact, and with the result that one or the other or both will be chipped or dented. Either or both occurrences are definitely to be avoided, not only for the reasons stated above, but additionally because of the time lost in play and the general resulting confusion.

With the above in mind, it is an object of the present invention to provide a so-called safety ball trap which will act automatically to prevent a bowling ball from rolling back beyond a given

point on the return runway should the ball lack sufficient momentum in its forward rolling movement to carry it up the usual incline and on to that part of the runway serving as a ball rack.

5 A further object of the invention is to provide a safety ball trap which not only acts automatically to trap and hold a ball against untoward backward rolling movement, but in addition, providing the momentum of the ball in its normal return movement is sufficient, acts automatically to admit of its passage freely and without retardation therebeyond and on to the ball rack.

A still further object of the invention is to provide a safety ball trap which is simple and fully automatic in its operation, which is inexpensive to manufacture and install, and which is usable on new as well as on existing bowling alley return runways with only minor modifications in the structure thereof.

20 Other objects and advantages of the invention will be hereinafter more fully set forth.

In the drawing, wherein like reference characters denote like or corresponding parts throughout the several views:

Fig. 1 is a side elevation of that portion of the ball return runway of a bowling alley to which the safety ball trap is attached;

Fig. 2 is an enlarged section on the line 2—2 of Fig. 1;

Fig. 3 is a side elevation of the safety ball trap illustrated in Fig. 2;

Fig. 4 is an enlarged section on the line 4—4 of Fig. 1;

Fig. 5 is a top plan view of the safety ball trap shown in Fig. 3; and

Fig. 6 is a fragmentary section showing the preferred construction of the ball stop.

The safety ball trap, designated in its entirety as 10, is shown in Fig. 1 as attached to the incline 11 of the ball return runway 12 of a conventional bowling alley 13. It comprises a steel frame or band 14 bent as shown in Fig. 2 to permit a standard bowling ball 15 to pass freely therethrough. The lower part of the band or

40 frame 14 is bent as indicated at 16 to fit the runway 12 which, as shown in Fig. 2, comprises spaced parallel rails or runners, and is further bent as at 17 to fit against the sides of a spacer block 18 to which it is fastened as by bolts 19. The reason for the spacer block will be herein-
45 after set forth.

The only movable or working part of the safety ball trap is shown enlarged in Fig. 6. Such part comprises a strong metal hinge 20 having an equally strong hinge pin 21. The reason for

making both the hinge and hinge pin strong is obvious, when it is considered that in the operation of the ball trap, the hinge and its pin are required to bear an impact load equivalent to that obtained by dropping a sixteen pound bowling ball thereagainst. One side of the hinge 20 is fastened to the band or frame 14 as by bolts 22 having their opposite ends extended beyond the opposite faces of the band. The other of the hinge sides is similarly fastened as by bolts 23 to a metal plate 24 so that normally the bolts 23 and 22, on the top or inner side of the band, engage one another, and due to such engagement hold the two hinged sides or plates at an angle one to the other of somewhat less than 90°.

Fastened to the hinge-supported plate 24 by the bolts 23 (or by other means if desired) are two pieces of durable leather 25—not too flexible. Two pieces of leather, it has been determined, give about the proper thickness and are somewhat more flexible than would be a single piece of the same thickness as the two. Also, they are much cheaper to replace when worn. Designedly, the leather pieces 25 are so placed and dimensioned that the top edges thereof extend slightly beyond the hinge pin 21, whereas the opposite lower edges thereof extend beyond the free end of the hinge-supported plate 24. Collectively, the hinge 20 and its associated or attached parts constitute the active ball stop member of the device. Note also that the extended edges of the leather pieces at the top of the plate 24 admit of clearness between the leather pieces and the hinge joint when the former are swung to the dotted line position shown in Fig. 6. The reason for thus extending the leather pieces is that they will, when swung into contact with the headed bolts 22, limit the extent of such upward swing. By thus limiting the upward swing of the ball stop, all tendency of the latter to remain in its upwardly swung position is avoided. Gravity immediately acts to counteract the upward swing and the ball stop will promptly fall the moment the ball in its normal return movement along the runway shall have passed through and beyond the frame.

For reasons hereinafter pointed out, the frame 14 is provided with bumpers 26 and 27. The bumpers 26 are preferably placed slightly above and one on either side of the center of the bowling ball as it passes through the frame, whereas the bumpers 27 are slightly larger and are preferably located one each on opposite sides of the ball stop hinge 21 and above the bumpers 26—suitable clearance for the passage of the ball through the band or frame 14 in each case being provided. Preferably, the bumpers 26 and 27 are of U-shape in cross-section, are made of leather, and are riveted or otherwise fastened to the band with their bight portions or rounded edges facing away from the ball in its normal return passage through the frame.

In addition to the bumpers 26 and 27, the frame or band 14 is provided with a so-called safety shield 28. This shield is fastened to the frame on the opposite side thereof from the ball stop and is large enough to prevent the retriever of a trapped ball from inadvertently putting his hand through the frame to push the ball out of the trap. Unless so prevented, there is always the danger that the ball retriever may have his fingers injured by a second ball which may, in the interim, have started its rolling return along the runway from the ball pit.

To install the trap, the spacer block 18 is first

removed so that the band can be passed around the runway 12 and put in the position shown in Fig. 1. When thus positioned, it is fastened to the runway by screws or other suitable means 5 29. The spacer block 18 is then replaced and bolted as at 19 to add strength not only to the runway but to the trap as well. Preferably, the width of the spacer block 18 is such that when the bolts 19 are drawn tight, the runners or rails of the runway will not be forced out of parallelism, as an added precaution, and to lend rigidity to the safety ball trap, a brace 30, shown in dotted lines, Fig. 1, may be extended downward therefrom to the floor of the alley 13.

Having thus described the construction of the safety ball trap, it now remains to briefly set forth the manner in which it operates. The trap is placed, as shown in Fig. 1, at a selected point on the incline 11 of the runway 12 with the hinge or movable part thereof facing the ball rack. Ordinarily, the ball 15 rolls along the runway on a fiber track 31 shown in Figs. 2 and 4, up the incline 11, through the frame or band 14, and hence beyond the trap 10, and, if its momentum is sufficient, finally up and on to the ball rack at the runway end. Assuming, now, that for one cause or another the momentum of the ball in its rolling return movement is insufficient to carry it beyond the position indicated by the oppositely pointing arrows of Fig. 1. In such case, and having attained such a position, the ball will hesitate a moment and then begin to roll back down the incline 11. Such backward rolling movement will continue until the ball comes in contact with the leather ball stop 25 which, by the time the backwardly rolling ball reaches it, will have assumed the full line position shown in Fig. 6 notwithstanding the fact that the ball in its forward rolling movement a moment earlier caused it to swing through the dotted line arc indicated in said Fig. 6. As the hinge will only close so far due to contact between the bolts 22 and 23, obviously there is insufficient space within the frame 14 for the ball to pass backwardly beyond the ball stop. In other words, the ball is trapped, as indicated by the full line showing of the ball 15 in Fig. 1. Since the trapped ball is predominantly disposed on the top side of the trap it is easy to retrieve, and without risk of injury in so doing, by merely lifting it off the runway with both hands. The retriever, by placing his hands on opposite sides of the ball, and lifting it out of the trap, avoids all risk of injury in so doing. Furthermore, the bumpers 26 and 27, in addition to preventing the backwardly rolling ball from jumping the track, act also as safety shields in that they prevent the retriever of the trapped ball from placing either hand between the ball and the then encircling band or frame.

A safety ball trap thus characterized is fully automatic in its operation, is completely fool-proof, is inexpensive to manufacture and install, and will, if adopted as standard bowling alley equipment, largely, if not wholly eliminate those constantly recurring injuries to which bowlers are subjected and which result from attempting to retrieve a ball having insufficient momentum to roll up the runway incline and on to the ball rack at the runway end.

While I have described my invention in detail in its present preferred embodiment, it will be obvious to those skilled in the art, after understanding my invention, that various changes and modifications may be made therein without de-

parting from the spirit or scope thereof. I aim in the appended claims to cover all such modifications and changes.

I claim as my invention:

1. In a bowling alley ball-return runway having an inclined portion adjacent to one end thereof, a safety ball-trap for said runway comprising a generally circular band adapted to bridge said inclined runway portion, a hinge comprising pin-jointed hinge plates one of which lies flat against said band and the other of which hangs loosely from said pin-joint, a non-metallic ball-stop member carried by said last mentioned hinge plate and adapted normally to occupy a position in the path of travel of a ball along said inclined runway portion and adapted immediately to return to normal position should it be momentarily displaced, and separate fastening means for attaching the hinge plates respectively to the band and to the ball-stop member, the fastening means being so disposed relatively to the ball-stop member as to limit its swinging movement.

2. In a bowling alley ball-return runway having an inclined runway portion adjacent to one end thereof, a safety ball-stop for said runway comprising a generally circular band, flattened intermediately of its ends, adapted to bridge said inclined runway portion, a hinge comprising pin-jointed hinge plates, said hinge being adapted to overhang one edge of said flattened band portion whereby one said hinge plate is free to swing in an arcuate path toward and away from a ball in its travel beyond said flattened band portion, a non-metallic ball-stop member carried by said swinging hinge plate member adapted normally to occupy a position in the path of travel of the ball along said inclined runway portion, means for fastening one said hinge plate to said flattened band portion, and means for fastening said ball-stop member to the other said hinge plate, said fastening means being so disposed that swinging movement of the ball-stop in one direction is limited by contact of the one said fastening means with the other whereas swinging movement of the ball-stop member in the opposite direction is

limited by contact of one said fastening means with the ball-stop member itself.

3. In a bowling alley ball-return runway having an inclined runway portion adjacent to one end thereof, a generally circular band, flattened intermediately of its ends, mounted to said runway and arranged to bridge said inclined portion thereof, a hinge comprising hinge plates, one of which is fastened to said flattened band portion and the other of which overhangs one edge thereof for free swinging movement toward and from said inclined runway portion, a non-metallic ball-stop member fastened to said swingable hinge plate, said ball-stop member being adapted to normally occupy a position in the path of travel of the ball along said inclined runway portion, and means for fastening the hinge plates respectively to the band and to the ball-stop member, said means being so disposed relatively to the band and to the ball-stop member as to limit the swinging movement of the latter under ball impact.

4. In a bowling alley ball-return runway having an inclined runway portion adjacent to one end thereof, a generally circular band, flattened intermediately of its ends, mounted to said runway and arranged to bridge said inclined portion thereof, a hinge comprising hinge plates, one of which is fastened to said flattened band portion and the other of which overhangs one edge thereof for free swinging movement toward and from said inclined runway portion, a non-metallic ball-stop member fastened to said swingable hinge plate, said ball-stop member being adapted to normally occupy a position in the path of travel of the ball along said inclined runway portion means for fastening the hinge plates respectively to the band and to the ball-stop member, said means being so disposed relatively to the band and to the ball-stop member as to limit the swinging movement of the latter under ball impact, and a shield fastened to and extending laterally out from said band along the edge thereof opposite to the overhanging hinge part for shielding the low side of the ball when trapped.

FRANCIS C. SAMS.
